FIG. 2 is a top, front left perspective view from a second side of the first embodiment of the cleaning robot;

FIG. 3 is a bottom, front right perspective view of the first embodiment of the cleaning robot;

FIG. 4 is a bottom, front left perspective view of the first embodiment of the cleaning robot;

FIG. 5 is a front view of the first embodiment of the cleaning robot;

FIG. 6 is the back view of the first embodiment of the cleaning robot;

FIG. 7 is a right side view of the first embodiment of the cleaning robot;

FIG. 8 is a left side view of the first embodiment of the cleaning robot;

FIG. 9 is a top view of the first embodiment of the cleaning robot;

FIG. 10 is a bottom view of the first embodiment of the cleaning robot;

FIG. 11 is a top, front right perspective view of a second embodiment of a cleaning robot;

FIG. 12 is a top, front left perspective view from a second side of the second embodiment of the cleaning robot;

FIG. 13 is a bottom, front right perspective view of the second embodiment of the cleaning robot;

FIG. 14 is a bottom, front left perspective view of the second embodiment of the cleaning robot;

FIG. 15 is a front view of the second embodiment of the cleaning robot;

FIG. 16 is the back view of the second embodiment of the cleaning robot;

FIG. 17 is a right side view of the second embodiment of the cleaning robot;

(Continued)

FIG. 18 is a left side view of the second embodiment of the cleaning robot;

FIG. 19 is a top view of the second embodiment of the cleaning robot; and,

FIG. 20 is a bottom view of the second embodiment of the cleaning robot.

The broken lines in the drawings are included for the purpose of illustrating portions of the cleaning robot that form no part of the claimed design.
